United States Patent Office.

ORSON ARMSTRONG, OF OSHKOSH, WISCONSIN.

Letters Patent No. 95,180, dated September 28, 1869.

IMPROVED SASH-BALANCE.

The Schedule referred to in these Letters Patent and making part of the same.

To all whom it may concern:

Be it known that I, ORSON ARMSTRONG, of the city of Oshkosh, State of Wisconsin, have invented a new and improved Balance-Sash and Adjustment; and I do hereby declare that the following is a full and exact description thereof, reference being had to the accompanying drawings, and to the letters of reference marked thereon, making a part of this specification.

The nature of my invention consists in the application of a ratchet and pawl to the side of a window-sash, as a means of support and adjustment, and the use of the same in combination with the upper and lower sash of a window, when the same are balanced and attached together with a cord, passing over an intermediate pulley, the ratchet being secured to the face of a stile of the lower sash, and the cord attached to the ratchet.

To enable others skilled in the art to make and use my invention, I will proceed to describe its construction and operation.

Figure 1 is a front elevation.

Figure 2 is a vertical cross-section, cutting through the cord and ratchet.

Figure 3 is an enlarged cross-section of the sash-stile and ratchet.

Figure 4 is a perspective view of the pawl enlarged. X X is a rectangular window-frame.

A A are window-sash.

B is a pulley.

c c c are friction-rollers, or bearings.

k is a cord.

d is an adjusting-ratchet, rabbeted on the back at d', to receive the lugs 3 3 of the pawl, fig. 4.

E is an adjusting-pawl, with a handle, E'.

F is a fastening-pawl.

The cord k is made fast to the upper sash at W. From thence it passes over the pulley B, and from thence down in front of the sash, and is secured to the pawl E.

The ratchet d is constructed with rabbets on the back, represented in cross-section at d' d', in fig. 3. The ratchet is firmly secured to the face of the window-stile.

The adjusting-pawl is constructed with lugs 3 3,

that ply in the rabbets d' d' in the ratchet d, and secures the pawl to service.

F is a pawl, that locks the sash when the window is closed, or when the top sash is partially closed.

Each sash is provided with friction-rollers, as shown at c c in fig. 1, that have their bearings against the jamb-casing of the window-frame, and thus allow easy vertical action of the sash.

In sash provided with a broad mortise-piece, or mulion-bar, in the centre, the ratchet d and pawl E may be fastened thereto, and the cord attached to the centre of the window, and thus used, as first described, without the aid of the friction-rollers c c.

The bearings of the friction-rollers c c, on the face of the jamb-casing, may likewise be faced with iron or sheet-metal.

Having described the several parts of my invention, I will now proceed to describe its operation.

The upper and lower sash being closed, as seen in fig. 1, relieve the fastening-pawl F; raise the lower sash in the usual manner, (the upper sash being attached to the lower sash, as described,) and the upper sash will be lowered in a corresponding degree.

To lower the upper sash, seize the pawl E, disconnect it from the ratchet, and allow the upper sash to drop to the desired position; then release your hold on the pawl, allowing the latter to again catch the ratchet.

To raise the lower sash, seize the pawl E, disconnect it from the ratchet, and hold firm while the lower sash is raised to the desired position, and release your hold, as last described.

Balance-sash, in and of themselves, are not new, and are therefore disclaimed.

What I claim as my invention, and desire to secure by Letters Patent, is—

The ratchet d and pawl E, when attached to the side of the sash, and used, in combination with the sash A A and cord k, as and for the purposes set forth.

ORSON ARMSTRONG.
